UNITED STATES PATENT OFFICE

136,100

DESIGN FOR AN AIRPLANE

George A. Page, Jr., Creve Coeur, Mo.

Application September 30, 1942, Serial No. 108,362

Term of patent 7 years

To all whom it may concern:

Be it known that I, George A. Page, Jr., a citizen of the United States, residing at Creve Coeur, State of Missouri, have invented a new, original, and ornamental Design for an Airplane, of which the following is a specification, reference being had to the accompanying drawings, forming a part thereof.

Fig. 1 is a top plan view of an airplane showing my new design.

Fig. 2 is a front elevational view.

Fig. 3 is a side elevational view; and

Fig. 4 is a top perspective view thereof.

I claim:

The ornamental design for an airplane as shown.

GEORGE A. PAGE, JR.
